UNITED STATES PATENT OFFICE.

JOHN TARANTO, OF WALTHAM, MASSACHUSETTS.

LOOM FEELER.

Application filed September 19, 1927. Serial No. 220,298.

The usual feeler used on looms of the automatic weft replenishing type consists of a detector finger which periodically enters the shuttle and feels for the filling on the bobbin and which, when the filling is exhausted or substantially exhausted, sets in operation the automatic weft replenishing mechanism, to the end that the emptied bobbin shall be expelled from the shuttle and replaced by a full bobbin. This type of feeler has become standard in the art, and various forms have been devised for the several standard makes of looms now in use.

My present invention is an improvement upon existing feelers of this type, and aims to provide a feeler which will be capable of that sensitiveness and adjustability which conditions of modern weaving require without, however, being unduly complicated as to structure; which will be positive and reliable in operation; simple of construction and installation, either as standard equipment, or as replacement for existing feelers; and which will have a constant tendency towards a safety position so that it may yield into such position of safety in the event that the bobbin or the shuttle should improperly contact the feeler, and by such contact call for a replenishment of filling before the filling on the active bobbin has in fact been substantially exhausted, thus resulting in a miss-pick.

The construction and operation of my feeler is described and shown in the accompanying specification and drawings, throughout which like reference numerals are correspondingly applied, and the characteristic features of novelty are particularly pointed out in the appended claims.

40 In the drawings:

Fig. 1 is a front elevation of a feeler in accordance with my invention.

Fig. 2 is an end view thereof.

45 Figs. 3 and 4 are detail views of the feeler itself removed.

Figs. 5 and 6 are detail views of the feeler retractor removed.

Fig. 7 is a fragmentary plan view illustrating the action of the feeler when a condition of sufficient filling exists on the active bobbin.

Fig. 8 is a similar view illustrating the action when a condition of insufficient filling exists on the active bobbin.

55 Fig. 9 is a section on the line 9—9 of Fig. 8.

Fig. 10 is a fragmentary detail particularly showing the bunter.

Fig. 11 is a front view partly broken away, particularly showing the release mechanism for the filled bobbin, and

Figs. 12 and 13 are sections on approximately the line 12—12 of Fig. 8 and showing the successive positions of the parts in effecting a change of bobbins in the shuttle.

My feeler may be described as a sliding and side slipping feeler, as distinguished from the usual pivoted feeler. It consists of a horizontally disposed base plate 1 having an attaching web 2 depending vertically therefrom. The web 2 is horizontally slotted as at 3 near its juncture with the plate 1 for a purpose which will be explained more fully hereinafter, and vertically slotted as at 4 to receive a clamping stud 5 by means of which the plate is adjustably fastened to the usual bracket 6 at the right hand front end of the loom frame 7.

In plan, the plate 1 is generally rectangular, but is laterally extended as shown at 8 at its back inner edge to provide a slideway. Beginning at its front edge the plate is slotted as at 9. This slot extends generally parallel to the outer lateral edge of the plate towards the rear edge of the plate but terminates short of said rear edge.

Mounted in said slot 9 for both backward and forward sliding movement and for limited arcual swinging movement is the reversely bent end 10 of a feeler arm 11, which is extended beyond the rear edge of the plate and is coiled upon itself as indicated at 12 and terminates in a serrated feeler finger 13 disposed for periodic entrance through the slots 14 and 15 of the shuttle binder 16 and shuttle S; respectively, when said slots are aligned with each other, whereby to feel for the filling F on the active bobbin B carried by said shuttle.

The position of the feeler arm 11 in the slot 9 is controlled by means of an adjustment lever 17 which is adjustably and pivotally held at 18 in the slot and is adapted to be moved into predetermined position with reference to the bent end 10 of said arm in the initial setting of the parts.

The arm 11 is spring tensioned as at 19, and is guided in an elongated slot 20 formed in an upstanding lip 21 at the rear edge of the plate 1. This lip is extended along the lateral extension 8 of the plate and with a shorter upstanding lip 22 formed on the

opposite edge of said extension defines a channeled guideway 23 for an actuating slide 24 which is adapted to be actuated by the feeler arm whenever a condition of insufficiency of filling exists on the active bobbin B.

The slide 24 is hooked or otherwise connected as at 25 with a blade actuating piece 26, which is adapted to be moved, against the action of a light coil spring, whenever a condition of insufficient filling on the active bobbin B exists, into the path of movement of a rocking blade 28 which is pivoted intermediate to a reciprocal rod 29 and is pivotally connected at its inner end as at 30 with the bobbin release mechanism, indicated generally at 31, which controls the successive supply of filled bobbins B' to the shuttle from the magazine M of the loom, this blade 28 in the normal operation of the mechanism rocking idly about its pivot 30 as the rod 29 reciprocates.

The upper edge of the member 26 and the lower edge of the adjacent free end of the blade 28 are serrated, as indicated at 32 and 33, respectively.

Disposed within the slot 3 of the web 2 for backward and forward sliding movement under certain conditions, is the arm 34 of a lay-actuated stud 35. The arm 34 projects beneath the plate 1 and lies rearwardly of the under portion of the reversely bent end 10 of the feeler arm 11 so as to act as a retractor for said feeler whenever the stud 35 is actuated.

Operated from the rocker blade 28 whenever a condition of insufficient filling on the active bobbin B exists, is the usual trip mechanism for the transference arm or hammer 36, which acts to transfer the filled bobbins successively from the bobbin magazine to the shuttle. Such trip mechanism includes a pivoted bunter 37 normally disposed out of line with the dagger 38 of the lay beam L of the loom, but adapted to be drawn up into alignment with said dagger by the trip rod 39, so as to be contacted by the dagger whenever a spent bobbin is to be replaced.

In operation, the feeler finger 13 enters the slot of the shuttle and feels for the filling on the active bobbin B at each forward swing of the lay beam. If the bobbin is full, the filling F simply slides the feeler forwardly along the base plate 1 as shown in full lines Fig. 7 against the tension of the coil spring 19 which returns the feeler to position to repeat this operation as the lay beam makes its return motion. In this action the blade 28 is rocked idly by the rod 29.

When the filling on the active bobbin B is exhausted, or substantially exhausted, however, the feeler finger 13 upon contacting said bobbin as the lay beam moves forwardly is caused to swing in the direction of the arrow A in Fig. 8, contacting the slide 24 and

shifting the member 26 into the path of rocking movement of the free end of the blade 28, whereupon downward movement of the rod 29 results in a downward pull being exerted on the pivot 30 with consequent actuation of the trip mechanism 31 and upward movement of the rod 39 which brings the bunter 37 into alignment with the dagger 38 on the lay beam (Fig. 12) so that the spent bobbin may be replaced by a filled bobbin.

This change is not effected however until the lay has made its return swing towards the back of the loom and has again swung forwardly towards the bunter. During this swing of the lay, the light coil spring 27 returns the slide 24 and feeler 13 to original position. On the next forward swing of the lay, the dagger 38 contacts the bunter 37 (Fig. 13) moving the feeler retractor 35 outwardly (Fig. 12) in the slot 9 and thereby positively withdrawing the feeler from the path of the shuttle, and swinging the bobbin transfer arm or hammer 36 downwardly (Fig. 13) to force the released filled bobbin B' into the shuttle which has now been returned home to the shuttle box at this end of the loom, and thereby eject the empty bobbin.

In the return motion of the lay, the parts 95 are automatically restored to their original positions in readiness to repeat the operation when the feeler again indicates an empty bobbin condition.

Should, for any reason, the shuttle itself 100 or any other part of the mechanism contact the feeler in such a way as to tend to swing the feeler in a direction away from instead of towards the slide 24 and blade 28, as might possibly be the case where the feeler has for any reason been shifted in an inoperative direction or where the shuttle has not properly entered the shuttle box, the mounting of the feeler as described permits the feeler either to pivot about the inner end of the member 105 17, if it is in contact with said member, or to pivot about its reversely bent portion disposed within the slot 9, if it is not in contact with said member 17, in the direction of the arrow A' in Fig. 7, away from the slide 24 as aforesaid, this motion being an idle motion and obviously without effect on the blade 28, so that mis-picks are prevented under such conditions in that the mechanism would not falsely indicate an empty bobbin 110 condition when as a matter of fact no such condition exists.

I appreciate that various modifications in the construction and arrangement of my feeler mechanism will be made as conditions require, and I regard all such modifications as within the preview of my invention, if within the limits of the appended claims.

What I therefore claim and desire to secure by Letters Patent is:

1. A device for operating the automatic weft replenishing mechanism of a loom, comprising a base plate having a slot therein normal to the path of movement of the active bobbin, a spring-tensioned feeler overlying said plate and having a mounting end disposed through said slot and bent beneath said plate and permitting said feeler movement in a path normal to the path of the active bobbin and side slipping movement in two opposite directions with respect to its path of normal movement, side slipping movement of said feeler in one direction being adapted to operate the weft-replenishing mechanism and side slipping movement of said feeler in the opposite direction being for purposes of safety, and an adjusting lever pivoted in said slot for controlling the position of said feeler.
- 20 2. A device for operating the automatic weft replenishing mechanism of a loom comprising a plate having a slot therein normal

to the path of movement of the active bobbin and a slot at its rear edge parallel to such path, a spring-tensioned feeler overlying said plate and having a feeler end guided through said parallel slot and a mounting end disposed through said normal slot and bent beneath said plate, the engagement of said bent end in said normal slot permitting said feeler movement in a path normal to the path of the active bobbin and side slipping movement in two opposite directions with respect to its path of normal movement, side slipping movement of said feeler in one direction being adapted to operate the weft-replenishing mechanism and side slipping movement of said feeler in the opposite direction being for purposes of safety, and an adjusting lever pivoted in said slot for controlling the position of said feeler.

In testimony whereof I affix my signature.

JOHN TARANTO.
